FOOD SERVICE KIOSK

George Rollin Goetz, Bloomington, Minn., assignor to
American Dairy Queen Corporation

Filed Dec. 30, 1974, Ser. No. 537,334

Term of patent 14 years

Int. Cl. D25—03

U.S. Cl. D25—1

FIG. 1.

FIG. 2.

FIG. 3.

FIG. 4.

FIG. 5.

FIG. 6.FIG. 7.

FIG. 1 is a front perspective view of a food service kiosk embodying my new design;

FIG. 2 is a front elevation view taken from the left of FIG. 1;

FIG. 3 is a top plan view thereof;

FIG. 4 is a front perspective view of an alternative embodiment of the food service kiosk of my new design;

FIG. 5 is a front elevational view taken from the left of FIG. 4;

FIG. 6 is a side elevational view taken from the right of FIG. 4; and

FIG. 7 is a top plan view thereof.

I claim:

The ornamental design for a food service kiosk, as shown and described.
